(57) **CLAIM**

The ornamental design for a heat exhauster for neck cooling device, as shown and described.

DESCRIPTION

FIG. 1 is a perspective view of the front, top and right side view of a heat exhauster for neck cooling device showing my new design;

FIG. 2 is a front view thereof;

FIG. 3 is a rear view thereof;

FIG. 4 is a left side view thereof;

FIG. 5 is a right side view;

FIG. 6 is a top view thereof;

FIG. 7 is a bottom view thereof;

FIG. 8 is a cross sectional view thereof, taken along line 8-8 in FIG. 2; and,

FIG. 9 is a cross sectional view thereof, taken along line 9-9 in FIG. 2.

1 Claim, 6 Drawing Sheets
